US0D1064743S

(12) **United States Design Patent** (10) **Patent No.:** **US D1,064,743 S**
(45) **Date of Patent:** **** Mar. 4, 2025**

(54) **BOTTLE**

(71) Applicant: **Shenzhen Zhongmin Technology Co., Ltd.**, Shenzhen (CN)

(72) Inventor: **Yitong Lin**, Guangdong (CN)

(**) Term: **15 Years**

(21) Appl. No.: **35/520,035**

(22) Filed: **Dec. 20, 2023**

(80) **Hague Agreement Data**

Int. Filing Date: **Dec. 20, 2023**

Int. Reg. No.: **DM/235046**

Int. Reg. Date: **Dec. 20, 2023**

Int. Reg. Pub. Date: **Feb. 16, 2024**

(30) **Foreign Application Priority Data**

Sep. 20, 2023 (CN) 202330615193.1

(51) **LOC (15) Cl.** **07-01**

(52) **U.S. Cl.**

USPC **D7/510**; D7/533; D7/392.1

Primary Examiner — April Rivas

Assistant Examiner — Tia Ruth-Renee Polidori

(57) **CLAIM**

The ornamental design for a bottle as shown and described.

DESCRIPTION

1. Bottle

1.1: Front

1.2: Rear

1.3 : Left

1.4 : Right

1.5: Top

1.6: Bottom

1.7 : Perspective

1.8 : Perspective

1.9 : Perspective

1.1 is a front view of a bottle showing my new design; 1.2 is a rear view thereof; 1.3 is a left view thereof; 1.4 is a right view thereof; 1.5 is a top view thereof; 1.6 is a bottom view thereof; 1.7 is a top, front and right side perspective view thereof; 1.8 is another top, front and right side perspective view thereof; and 1.9 is a bottom, rear and left side perspective view thereof.

The broken lines in the drawings depict portions of the bottle that form no part of the claimed design. The “SUPER SPARROW” logo forming no part of the claimed design is a registered trademark of SHENZHEN ZHONGMIN TECHNOLOGY CO., LTD.. The “” logo forming no part of the claimed design is a registered trademark of SHENZHEN ZHONGMIN TECHNOLOGY CO., LTD.

1 Claim, 9 Drawing Sheets
